UNITED STATES PATENT OFFICE.

RUFUS S. MERRILL, OF WAKEFIELD, ASSIGNOR OF ONE-HALF TO CHARLES F. QUINCY, OF BOSTON, MASSACHUSETTS.

CAR OR OTHER ROOF.

SPECIFICATION forming part of Letters Patent No. 431,474, dated July 1, 1890.

Application filed April 2, 1890. Serial No. 346,314. (No model.)

To all whom it may concern:

Be it known that I, RUFUS S. MERRILL, of Wakefield, in the county of Middlesex and State of Massachusetts, have invented a certain new and useful Improvement in Car or other Roofs, of which the following is a specification.

My invention has particular reference to the construction of car-roofs; but some of its features are applicable also to roofs of other structures.

It is intended to provide a cheap, easily and quickly constructed and thoroughly water-proof roof, and it can best be explained and understood by reference to the accompanying drawings, in which—

Figure 1 is a plan view of the top of a car with the outer roof removed. Fig. 2 is a cross-section of the car-roof on line 2 2, Fig. 1. Fig. 3 is a longitudinal section of the roof on line 3 3, Fig. 1. Fig. 4 is an enlarged detail view of a portion of the roof, showing batten, water-proof material, and the grooved cap arranged in accordance with my invention.

25 A is the car-body.

B represents the inner roof or ceiling of the car supported upon and secured to the carlings C in the usual way. This inner roof is composed of boards laid lengthwise of the car, which need be planed or smoothed off upon their inner faces only. This inner roof or ceiling is covered with any approved waterproof paper or fabric. Strips D of this fabric are laid crosswise of the roof, each strip 35 extending in one continuous length between the eaves and over the ridge of the roof. Along the lines where the contiguous edges of these strips overlap battens E are secured to the inner roof B. The contiguous edges of 40 the strips are overlapped upon and nailed or tacked to the tops of these battens, as seen in Figs. 3 and 4. Then upon these battens, to which the overlapping edges of the strips have been secured, are placed grooved wooden 45 caps F, which fit down closely upon and around the battens, drawing the strips out smooth and tight upon the inner roof and extending continuously from the eaves to the ridge where they meet. The joint which they 50 form at the ridge should be covered by a con-

tinuous longitudinal ridge-piece, extending from end to end of the car. This ridge-piece consists in the present instance of the meeting ends of the transverse boards, which compose the outer roof G of the car, and the longitudinal foot-board or tread H, which covers these meeting ends. The caps F form in effect rafters intermediate of the outer and inner roofs, on which are secured the longitudinal stringers I, to which the boards which 60 form the outer roof are nailed. The combined caps and rafters F are nailed to the battens, or battens and inner roof. It is manifest that for roofing or sheathing buildings or other structures in which the water-proof 65 fabric does not require external protection the outer roof or sheathing G and its stringers I may be dispensed with.

I am aware that it has before been proposed to build a car-roof with an outer and inner 70 roof and an intermediate layer of tar or other waterproofed paper or fabric applied to the exterior of the inner roof. I am also aware that in such a roof it has been proposed to lay the water-proof fabric in strips crosswise 75 of the car between rafters of T shape approximately with the edges of the strips laid up against the sides of the rafters, so as to reach to a point just under the flanges or heads on the tops of the rafters, and to cover 80 these edges by water-proof paper or fabric caps applied to the rafters, so as to cover the exposed edges of the strips, and held in this position by stringers notched so as to fit on the rafters at the points where the two meet. 85 I claim none of these things.

In my roof the strips at their edges are covered and held by continuous wooden caps, which serve as rafters as well, fitting down over the battens to which the strips are secured, protecting and covering the overlapping edges of these strips so as to make a water-tight joint, stretching and holding taut the fabric, and at the same time serving as rafters to which the stringers which carry the 95 outer roof may be secured.

What I claim, and desire to secure by Letters Patent, is—

1. The combination of the inner roof or sheathing B, the battens E, the water-proof 100

strips D, having their contiguous overlapping edges secured to the battens, and the continuous grooved wooden caps F, covering the edges of the fabric and fitting closely upon 5 and around the battens and down upon the body of the fabric on the inner roof, as and for the purposes hereinbefore shown and set forth.

2. The combination of the inner roof B, the 10 battens E, the water-proof strips D, having their contiguous overlapping edges secured to the battens, the continuous grooved wooden

combined caps and rafters F, fitting down upon and around the battens, and the stringers I, secured to said parts F and the outer roof 15 G, as and for the purposes hereinbefore set forth.

In testimony whereof I have hereunto set my hand this 28th day of March, 1890.

RUFUS S. MERRILL.
